(57) **CLAIM**

The ornamental design for an end cap of a smoking article, as shown and described.

DESCRIPTION

FIG. 1 is a right side perspective view of an end cap of a smoking article showing a first embodiment of my new design.

FIG. 2 is left side perspective view thereof.

FIG. 3 is a front elevational view thereof.

FIG. 4 is a rear elevational view thereof.

FIG. 5 is a top plan view thereof.

FIG. 6 is a bottom plan view thereof.

FIG. 7 is a left side elevational view thereof.

FIG. 8 is a right side elevational view thereof.

FIG. 9 is a right side perspective view of an end cap of a smoking article showing a second embodiment of my new design.

FIG. 10 is left side perspective view thereof.

FIG. 11 is a front elevational view thereof.

FIG. 12 is a rear elevational view thereof.

FIG. 13 is a top plan view thereof.

FIG. 14 is a bottom plan view thereof.

FIG. 15 is a left side elevational view thereof; and,

FIG. 16 is a right side elevational view thereof.

The broken line showing is for illustrative purposes only and forms no part of the claimed design.
